UNITED STATES PATENT OFFICE.

ROMAN ZELESZKIEWICZ, OF CHICAGO, ILLINOIS, ASSIGNOR OF ONE-HALF TO JOSEPH MECHOCKI, OF CHICAGO, ILLINOIS.

LIFE-PRESERVING SUIT.

1,122,459.

Specification of Letters Patent. Patented Dec. 29, 1914.

Application filed October 13, 1914. Serial No. 866,428.

To all whom it may concern:

Be it known that I, ROMAN ZELESZKIEWICZ, a citizen of the United States, residing at Chicago, in the county of Cook and State of Illinois, have invented certain new and useful Improvements in Life-Preserving Suits, of which the following is a specification.

This invention relates to certain new and useful improvements in life preserving suits.

The primary object of the invention is to provide a foldable inflatable float having a pair of trousers attached centrally thereof after the manner of the "breeches buoy" and serviceable as a life preserver.

A further object is to provide a float of boat form and having trousers formed centrally positioned therewith and whereby the wearer may enter the trousers with the float positioned surrounding the waist and may manually fill the float with air for sustaining the same upon the surface of the water.

A still further object is to provide a foldable boat-shaped float adapted for supporting a person upon the surface of the water in a proper position for treading water and thereby navigating for short distances.

With these general objects in view and others that will appear as the nature of the invention is better understood, the same consists in the novel combination and arrangement of parts to be hereinafter more fully described, illustrated in the accompanying drawings, and set forth in the appended claim.

In the drawings forming a part of this application and in which like-designating characters refer to corresponding parts throughout the several views, Figure 1 is a central vertical longitudinal sectional view through the device illustrating a man positioned therein. Fig. 2 is a top plan view of the device. Fig. 3 is a vertical central transverse sectional view thereof with the trouser legs broken away, and Fig. 4 is an enlarged detail perspective view of one side of the central portion of the foldable frame of the float.

Referring more in detail to the drawings, the invention broadly consists in the provision of a boat-shaped float 10 having a pair of trousers 11 centrally positioned therein and with the trouser legs 12 depending therefrom and adapted to receive a person such as the man 13 illustrated in Fig.

1, and having closed feet portions 26. The float 10 is formed of an upper and a lower frame 14 and 15 respectively, and spaced apart by hinged braces 16 allowing the frames to be folded together by means of the hinges 17 of said braces which fold outwardly away from each other. A flexible cover 18 is secured over the framework thus formed and the same may be provided of canvas or rubber or other suitable material and is herein illustrated as formed of rubber, and having portions 19 thereof molded around the frames 14 and 15 for securely positioning the cover upon the frame.

The trousers 11 are provided with a belt 70 or waist band 20 which is made in the form of a watertight joint with a reinforcing wire 27 embedded therein and between the float cover 18 and the trousers as best illustrated in Fig. 3 is being understood that the trousers extend centrally through the float with the belt 20 forming a circular opening in the top thereof, while the trouser legs 12 depend beneath the float and provide two leg-openings 21 in the bottom of the float. The 75 trousers being secured by air tight joints with the float, the body-portion 22 thereof forms a centrally positioned tubular wall traversing the float vertically so that the interior of the float comprises a single air and 80 water tight compartment.

An air pump 23 is provided upon the float and adapted to be actuated by the occupant thereof in pumping air through the pipe 24 to the interior of the float for 85 inflating the same and rendering it buoyant for supporting the person occupying the trousers. An air outlet valve 25 is provided upon the cover 18 to allow the air to escape from the float so the same may be folded 90 when desired by folding the braces 16 and positioning the frames in contact with each other. Cross braces 28 are provided for 95 each frame upon opposite sides of the trousers.

From this detailed description of the device the complete operation thereof will be apparent in that when desired for use as a floating life-preserver, a person may put on the trousers by unfolding the float member 105 and may then inflate the float by means of the pump 23 and in which position the wearer will be supported in an upright floating position.

While the forms of the invention herein 110

shown and described are what are believed to be the preferable embodiments thereof, it is nevertheless to be understood that minor changes may be made therein without departing from the spirit and scope of the invention as set forth in the claim.

What I claim as new is:—

10 A device of the class described comprising a boat shaped float member formed of an upper and a lower frame, foldable braces connecting the said frames, a flexible cover surrounding the said frames and forming an inflating chamber therein, a pair of trousers centrally positioned through said float mem-

ber and chamber and having leg and feet 15 portions depending therefrom, an inflating pump and an outlet valve for said chamber positioned upon the upper side of said float member, portions of the said frames being embedded in the material forming the flexible cover therefor.

In testimony whereof I affix my signature in presence of two witnesses.

ROMAN ZELESZKIEWICZ.
